UNITED STATES PATENT OFFICE.

JAMES B. STANWOOD, OF CINCINNATI, OHIO, ASSIGNOR TO THE LANE & BODLEY COMPANY, OF SAME PLACE.

VALVE-ROD CONNECTION.

SPECIFICATION forming part of Letters Patent No. 313,961, dated March 17, 1885.

Application filed October 27, 1884. (No model.)

To all whom it may concern:

Be it known that I, JAMES B. STANWOOD, a citizen of the United States, residing at Cincinnati, Ohio, have invented new and useful 5 Improvements in Valve-Rod Connections, of which the following is a specification.

My invention relates to valve-actuating mechanism in variable cut-off steam-engines employing valve motion wherein the exhaust and entrance ports are opened and closed by a rotary motion of the valve stems; and it consists in an improved construction of the valve-stem bearings and crank-connections, as more fully hereinafter pointed out. In "Corliss" engines of this class the valve-actuating mechanism usually consists of an oscillating plate arranged centrally between the valve-stems to which are attached circumferentially four radial arms in operative connection with the 10 valve-stem cranks, two upper ones actuating the steam-receiving ports, and two lower ones the steam-exhaust ports. Auxiliary arms on the receiving-port cranks carry vertical rods actuating pistons in "dash-pots" beneath. 15 Upon the opening of the entrance-ports for admission of steam to the cylinder the pistons in the dash-pots are raised successively against the pressure of the air, a vacuum being produced beneath, the object being to produce 20 a quick cut-off on release of the valve-stem. In this operation there is considerable strain brought upon the valve-stems, tending to bend or spring them, and in a less degree the same is true of the exhaust-port valve-stems, as in 25 both the cranks overhang their bearings, bringing their weight and that of the connecting-rods upon the valve-stems.

The ordinary construction, in which the valve-stem projects outward beyond its supporting-structure, carrying the weight of the cranks and receiving their strains at that point, renders this a serious difficulty; and it is the object of my invention to make such a connection of the actuating-cranks to the valve-stems as 40 to support the cranks and valve-stems as to relieve the latter of all strains, except torsional ones, their true function.

Mechanism illustrating my improvement is exhibited in the accompanying drawings, in which—

Figure 1 is a vertical longitudinal section of exhaust-valve stem in its supporting bearings or bonnets embodying my improvement. Fig. 2 is a perspective view of the same, and Fig. 3 a vertical longitudinal section of entrance-valve stem and support embodying my improvement.

The parts hereinafter mentioned are designated by suitable letters of reference.

In the drawings, B designates the bonnets attached to the side of steam-chest; D, the cranks keyed to the valve-stems V by keys e. C is the exhaust-port crank-arm, actuated by radial arm A from the oscillating plate; C', the entrance-port crank-arm, actuated by radial arm A''' and crank-pin A''. An auxiliary crank-arm (not shown) carries the dash-pot rod d on crank-pin A'.

G is the governor-cam collar actuating the variable cut-off. These parts are of the usual construction, and require no further description, except as modified by my improvements, hereinafter pointed out.

Instead of simply boring the exhaust-cranks D for the valve-stems and then keying the latter thereon outside of the bonnets so that the weight and strain will be all borne by the stem itself, I extend the hub d' of the cranks laterally and counterbore the same to fit over and oscillate upon the outer turned ends, S, of the bonnets, the cranks thus riding upon the bonnets at S as journals. The cranks being now keyed upon the valve-stems at the outer ends of the hubs, the valve-stems are relieved of the weight of the cranks and rods and of all transverse strains, which are borne by the journals S of the supporting-bonnets. A precisely similar construction is followed with the entrance-port bonnets and cranks, with the exception that a narrow space surrounding the journal at its inner end is left for free insertion of the governor-cam collar G vertically over the actuating-arm A'', in order that proper action of the variable cut-off may take place. I thus secure an accurate and even motion and wear of the valve-stem, which may fit loosely in the bonnet and reduce the friction of the valve and stem. Moreover, the stem, being relieved from all but torsional strains, may be made smaller, and a saving in labor and ma-

material further effected both in construction and repairs, owing to the cheapness and permanence of this bonnet as compared with the cost of renewing valve stems and bonnets of the old pattern.

I claim and desire to secure by Letters Patent of the United States—

1. The herein-described improvement in steam-engines employing valve-gear of the kind described, consisting in bonnets B, provided at their outer ends with journals S, adapted for holding thereon as a journal-bearing in operating contact a correspondingly counterbored crank, D, substantially as and for the purpose specified.

2. In steam-engines with valve motion, as described, cranks D, with suitable arm or arms for attachment of operating-levers, centrally bored for passage of valve-stems, and counter-

bored to fit in operative contact upon journals S at the outer ends of the bonnets, adapted, if required, for the insertion of the governor-cam collar in suitable operative position, substantially as shown and described.

3. The combination, with a steam-cylinder and valve-gear of the class described, of bonnets B, with journaled outer ends, and cranks D, counterbored to fit and ride upon the bonnet-journals, arranged and operating substantially as described.

In testimony whereof I have hereunto set my hand in the presence of two subscribing witnesses.

JAMES B. STANWOOD.
